UNITED STATES PATENT OFFICE.

JOHN F. GAIL, OF EVANSTON, ILLINOIS, AND CHARLES H. BUSCH, OF KENOSHA, WISCONSIN, ASSIGNEES TO SIMMONS COMPANY, OF KENOSHA, WISCONSIN, A CORPORATION OF DELAWARE.

BEDSTEAD CORNER LOCK.

Application filed April 15, 1921. Serial No. 461,605.

To all whom it may concern:

Be it known that we, JOHN F. GAIL and CHARLES H. BUSCH, citizens of the United States, residing at Evanston, in the county of Cook and State of Illinois, and at Kenosha, in the county of Kenosha and State of Wisconsin, respectively, have invented certain new and useful Improvements in Bedstead Corner Locks, of which 10 the following is a specification.

Our invention relates to improvements in bedstead corner locks and refers to a type of corner lock used for connecting the head end and foot end of a bedstead by means of 15 side rails preferably of angular cross section.

The principal objects of our invention are to provide a corner lock which may be constructed of stamped sheet metal or rolled 20 shapes; to provide a construction which will admit of the use of a side rail having an angular cross section throughout its length, and having its ends devoid of projecting parts; to provide a corner lock of 25 the type described which may be disconnected from the bedstead end frame without the use of special tools or appliances and which may be assembled with equal facility; to provide a corner lock having attaching 30 and adjusting means accessible from the exterior of the bedstead; to provide a corner lock which shall be rugged and substantial in construction while being simple and economical in design and manufacture, and 35 in general, to provide an improved efficient corner lock of the character referred to.

In the drawings, which illustrate a specific application of our invention to a tubular metallic bedstead.

Fig. 1. is a side elevation of the corner lock showing the bed post and the side rail connected thereto by our improved corner lock.

Fig. 2 is a section taken on the line 2—2 45 of Fig. 1.

Fig. 3 is a section taken on the line 3—3 of Fig. 2.

Fig. 4 is a plan view of the corner lock, and

50 Fig. 5 is a perspective view of a stiffening member.

Referring to the drawings, it will be observed that although we have not shown a complete bedstead, it will be understood

that the bedstead frame comprises the 55 usual four corner posts, one of which 10 is shown fragmentarily, the corner posts on the same side of the bedstead being connected by side rails, one of which is shown at 11. In the particular bedstead to which 60 our improved corner lock is shown applied, the post 10 is of tubular form, its cross section being substantially that of a square, as indicated in Fig. 4. The side rail 11 preferably is of angle iron construction as 65 best shown in Fig. 2 of the drawings.

The purpose of the corner lock is to connect the end of the angle iron 11 to the corner post 10 of the bedstead frame, the arrangement being preferably such that 70 the angle iron 11 may be turned end for end through a vertical plane in order to bring the horizontal flange 12 of the side rail either at the top of the vertical flange 12 or at the bottom thereof. Such reversible construction is desirable to enable the same bedstead frame to be used with bottoms or springs of different types as is well understood by those skilled in the art.

The corner lock herein shown is in the 80 nature of a development or an improvement on the corner lock illustrated and described in Frank Kusterle, Patent No. 1,411,362, dated April 4, 1922, which is owned by the assignee of this application.

In that general type of corner lock for which our invention is particularly well adapted, the side rail 11 is insertable into a socket having a pair of optional corner seats for receiving the end of the 90 angle iron and equipped with suitable wedging or clamping means for detachably securing the end of the angle iron rigidly in the socket. As shown in the drawings, the said socket in the present instance comprises as its principal part a sheet metal stamping of inverted U shape in cross section, the top 14 of the U being horizontal and the legs 15 and 16 thereof depending from the part 14 in vertically parallel 95 relation. The part 14 and the upper portions of the spaced sides 15 and 16 constitute three sides of the rectangular socket, the remaining or bottom side of the socket being formed by the end of a cross rail or tie member 17, which connects together the two posts of the bedstead end.

The rail 17 besides serving as a connection

between the two corner posts and as one side of the rectangular side rail socket, also serves to connect together in properly spaced relation the lower ends of the side members 15 and 16 of the socket stamping. To this end the flanges 18 and 19 of said cross angle 17 are shouldered or reduced in width as shown at 20 in order to pass through an L shaped opening punched in the side wall 16, the shoulder 20 being effective to prevent outward movement of the side member 16 away from the side member 15. The extremity of the said angle iron 17 is further reduced in width to pass through a smaller L shaped opening punched in the side member 15, the reduced extremity being of sufficient length to enable it to be riveted over to form an enlarged L shaped head as shown best at 21 in Fig. 1. It will be understood that the plate 15 is thus rigidly locked to the extremity of the cross angle 17, outward movement of the plate 15 being prevented by the head 21 and inward movement of the plate with reference to the cross angle being prevented by the shoulder 22.

The socket as a whole is detachably secured to the hollow bed post 10 by means of a bolt or cap screw 23, said cap screw passing freely through an aperture 24 punched in the cross angle centrally of the socket and through apertures 25 and 27 punched respectively in the wall 26 of the post and in the stiffening plate 28, which plate preferably is interposed between the abutting edges of the stamping and the relatively thin post-wall 26.

The bolt or screw 23 has its inner end suitably threaded to screw into a liner-plate 29 inserted in the post, the wall 26 of the post being rigidly clamped between the stiffening plate 28 and said liner 29. Preferably the plates 28 and 29 extend vertically a distance substantially corresponding with the length vertically of the socket and, if desired, may be made of lengths of rolled metal. On the side edges of the outer stiffening plate 28 there are pairs of rudimentary flanges 29' and 30, which serve to accurately position the post and the socket relative to each other, and prevent skewing of socket on the post. Also, we prefer to make the width of the liner 29 such that it may be readily inserted in the post while at the same time it is wide enough to provide the maximum stiffening or clamping effect.

In view of the fact that bedsteads are occasionally assembled by persons having little or no mechanical skill and judgment and because of the relative thinness of the cross angle 17, there may be at times a tendency to bend or buckle the end of the cross angle 17 when tightening up the bolt or screw 23 in assembling the corner lock. In order to avoid this possible trouble, we prefer to employ a stiffening washer 31 punched to admit

loosely the screw 23 and interposed between the extremity of the angle iron and the head 32 of said bolt.

In order to avoid the necessity of making the stiffening washer 31 of excessive thickness it may be formed of a short length of angle iron, the horizontal flange 33 of the angle iron being of slightly less depth than sufficient to engage the liner 28. The stiffening washer 31 also serves as a spacing member for holding apart the lower ends of the side walls 15 and 16 of the socket, it being understood that although the side plate 16 is prevented from moving outwardly by the shoulder 20, there is no internal shoulder for preventing the side wall 16 from approaching the opposite side wall 15 of the socket.

The specific clamping means for the end of the side rail 11 may be of any desired type. In the present embodiment, we have shown a construction similar to that shown in the Kusterle patent heretofore referred to and comprising a pair of mating diagonal wedge blocks 34 and 35, through which passes a clamping bolt 36. The head 37 of said bolt 36 is preferably located on the exterior face of the said socket, the bolt passing through both walls of the latter. Tightening up of the wedges 35 and 36 is effected by means of a nut 38 fitting the threaded inner end of the bolt 36 and impinging against a sleeve-like washer 40, which engages the outer face of the wedge block 35. The aperture in the wall 16 through which the bolt 39 passes is preferably large enough to admit freely the washer 40 so that the latter can be made long enough to bring the nut 38 well outside of the socket in an accessible position.

In order to hold the mating wedge parts 34 and 35 in proper relative position it is preferable to insert in the space between said wedge parts, a light steel plate spring 41, which takes the form of a length of spring steel bent over into a C shape and centrally apertured to admit the bolt 36.

The end of the angle iron side rail 11 is preferably slotted as indicated by dotted lines in Fig. 1 at 42 so that it is unnecessary to withdraw the bolt 36 in order to insert or remove the end of the side rail.

The details of construction and operation herein described are merely illustrative of a specific application of our invention, the scope of which should be determined by reference to the appended claims, said claims being construed as broadly as possible consistent with the state of the art.

We claim as our invention:

1. In a bedstead corner lock, the combination of a post, a side rail, a socket therefor having a pair of spaced substantially vertical walls, a cross rail for connecting said socket to another part of the bedstead con-

necting said walls and constituting another wall of the socket, and a threaded member co-operating with the portion of the cross rail between said walls for securing the 5 socket to the post.

2. In a bedstead the combination of a corner post, a socket including a one piece sheet metal stamping folded intermediate its ends to form a member of inverted U shape, a side 10 rail securable in said socket, a cross rail for laterally positioning said post and socket, and having its end extending through both of the limbs of the U and connecting together the said limbs, and a connecting member 15 passing through and operating upon said rail end for securing the post and socket together.

3. In combination a corner post, a socket comprising a one piece sheet metal stamping 20 folded intermediate its ends to form a member of inverted U shape, a side rail removably secured in said socket, a cross rail for laterally positioning said post and socket, and having its end extending through both 25 of the limbs of the U and connecting to-

gether the said limbs, a connecting member passing through and operating upon said rail end for securing the post and socket together, and a member interposed between said walls for spacing the same apart and 30 constituting a stiffening means for said rail end.

4. In combination, a tubular corner post, a rectangular socket including a sheet metal stamping of inverted U shape in vertical 35 cross section having its edges abutted against the post, a cross rail extending laterally from the socket and having its end inserted through both of the depending limbs of the U and constituting the bottom wall of the 40 socket, the other walls of which are formed by the U shaped member, a screw extending through the wall of the post and through the end of said cross rail for securing said socket to the post, a side rail insertable in 45 said socket and means for clamping said side rail in the socket.

JOHN F. GAIL.
CHARLES H. BUSCH.
